UNITED STATES PATENT OFFICE.

JOSEPH A. MARINER, OF CHICAGO, ILLINOIS.

DESIGN FOR A COLLAR-HOLDER.

55,568.

Specification for Design.

Patented June 29, 1920.

Application filed August 28, 1919. Serial No. 320,539. Term of patent 14 years.

To all whom it may concern:

Be it known that I, JOSEPH A. MARINER, a citizen of the United States, residing at Chicago, in the county of Cook and State of Illinois, have invented a new, original, and ornamental Design for Collar-Holders, of which the following is a specification, reference being had to the accompanying drawing, forming part thereof.

Fig. 2 is a view looking at the front edge of the same.

I claim:

The ornamental design for a collar holder, as shown.

JOSEPH A. MARINER.
